UNITED STATES PATENT OFFICE.

CHARLES JOHN NOKE, OF STOKE-UPON-TRENT, ENGLAND, ASSIGNOR TO
WILLIAM S. PITCAIRN, OF NEW YORK, N. Y.

DESIGN FOR A JUG OR SIMILAR ARTICLE.

No. 38,051.

Specification for Design.

Patented June 5, 1906.

Application filed April 16, 1906. Serial No. 312,032. Term of patent 3½ years.

To all whom it may concern:

Be it known that I, CHARLES JOHN NOKE, a subject of the King of Great Britain, residing at Stoke-upon-Trent, England, have invented a certain new, original, and ornamental Design for Jugs or Similar Articles, of which the following is a specification.

In the accompanying drawing the figure is

an elevation showing the design for the jug.

What I claim is—

The ornamental design for a jug or similar article substantially as shown.

CHARLES JOHN NOKE.

Witnesses:

JOHN WILLIAM LATIMER,

JOHN HENRY COPESTAKE.
